(57) **CLAIM**

The ornamental design for a smartphone mount for vehicles, as shown and described.

DESCRIPTION

FIG. 1 is a front-perspective view of a smartphone mount for a vehicle in an open position showing my new design;

FIG. 2 is a rear-perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a front-perspective view of the smartphone mount in a closed position;

FIG. 10 is a rear-perspective view of the smartphone mount in a closed position;

FIG. 11 is a front elevational view of the smartphone mount in a closed position;

FIG. 12 is a rear elevational view of the smartphone mount in a closed position;

FIG. 13 is a left side elevational view of the smartphone mount in a closed position;

FIG. 14 is a right side elevational view of the smartphone mount in a closed position;

FIG. 15 is a top plan view of the smartphone mount in a closed position;

FIG. 16 is bottom plan view of the smartphone mount in a closed position; and,

FIG. 17 is a perspective view of the smartphone mount with the smartphone mounted.

The broken line showing of environment is for illustrative purposes only and forms no part of the claimed design.
